[57] CLAIM

The ornamental design for a sculptural air balloon at-
tachment for a gift basket, substantially as shown and
described.

DESCRIPTION

FIG. 1 is an oblique view of a sculptural air balloon
attachment for a gift basket showing my new design;
FIG. 2 is an elevational view of the opposite side;
FIG. 3 is an elevational view of the opposite end; and
FIG. 4 is a bottom plan view.The broken line disclosure of a basket in FIGS. 1-4 is
intended solely to illustrate the environment of the
claimed design.Fig. 1
